Primary Examiner — Jonathan J Han(74) *Attorney, Agent, or Firm* — Marshall A. Lerner; Steven J. Kim; KLEINBERG & LERNER, LLP(57) **CLAIM**

The ornamental design for a shoe upper as shown and described.

DESCRIPTION

FIG. 1 is a front perspective view of a shoe upper in accordance with my new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The dash-dash broken lines in the drawings represent portions of the shoe upper and environmental structure that form no part of the claimed design. The dot-dash broken lines in the drawings define the bounds of the claim and form no part thereof. The surfaces devoid of shading lines are not claimed.
